(57) **ABSTRACT**

A backplane connector includes a housing and a number of mounting modules. The housing includes a base defining a number of receiving grooves. The mounting modules are assembled to the receiving grooves. Each mounting module includes an insulating body, a terminal module installed in the insulating body, and a metal shield surrounding member sleeved on the insulating body. The metal shield surrounding member includes a surrounding portion and a mounting portion extending downwardly from the surrounding portion. The surrounding portion is formed by four side walls so as to form a fully-enclosed shielding cavity. As a result, the shielding effect and the grounding return effect of the backplane connector are improved.

**BACKPLANE CONNECTOR WITH
IMPROVED METAL SHIELD
SURROUNDING MEMBER**

**CROSS-REFERENCE TO RELATED
APPLICATIONS**

This patent application is a continuation-in-part of U.S. patent application Ser. No. 17/341,129, filed on Jun. 7, 2021, which claims priority of a Chinese Patent Application No. 202010567796.4, filed on Jun. 19, 2020 and titled “BACK-PLANE CONNECTOR ASSEMBLY”, and a Chinese Patent Application No. 202021709484.4, filed on Aug. 17, 2020 and titled “BACKPLANE CONNECTOR”, the entire content of which is incorporated herein by reference.

TECHNICAL FIELD

The present disclosure relates to a backplane connector which belongs to a technical field of connectors.

BACKGROUND

Existing backplane connectors generally include a housing and a plurality of terminal modules mounted to the housing. Each terminal module includes an insulating block, a plurality of conductive terminals fixed to the insulating block, and a metal shield surrounding member provided on a periphery of the insulating block. Each conductive terminal includes a contact portion for mating with a mating backplane connector and a mounting portion for being connected with a circuit board. In order to keep the mounting portions of the terminal modules in a positional relationship with each other so as to be mounted to the circuit board, some existing backplane connectors are further provided with a mounting block installed at a bottom of the terminal modules. The mounting block is usually made of insulating material, and defines a plurality of mounting holes for the mounting portions of the conductive terminals to pass through.

A metal shield surrounding member in the related art includes a surrounding portion and a mounting portion extending downwardly from the surrounding portion. The mounting portion is roughly U-shaped. The surrounding portion includes a first side wall, a second side wall opposite to the first side wall, a third side wall connecting one end of the first side wall and one end of the second side wall, and a fourth side wall connecting the other end of the first side wall and the other end of the second side wall. The mounting portion includes a fifth side wall located on a same side as the first side wall, a sixth side wall located on a same side as the third side wall, and a seventh side wall located on a same side as the fourth side wall. The fifth side wall is connected to the first side wall. The sixth side wall is located outside the third side wall and is disconnected from the third side wall. The seventh side wall is located outside the fourth side wall and is disconnected from the seventh side wall.

When the backplane connector is mated with the mating backplane connector, the grounding return can only be realized through the first side wall and the fifth side wall connected thereto. In other words, since the sixth side wall is disconnected from the third side wall and the seventh side wall is disconnected from the fourth side wall, the grounding return cannot be realized directly through the third side wall and the sixth side wall, nor directly through the fourth side wall and the seventh side wall.

Therefore, it is desirable to improve the metal shield surrounding member in the related art to improve shielding effect and grounding return effect.

SUMMARY

An object of the present disclosure is to provide a backplane connector with improved shielding effect and improved grounding return effect.

In order to achieve the above object, the present disclosure adopts the following technical solution: a backplane connector, including: a housing including a base, a first side wall portion extending from one end of the base, and a second side wall portion extending from another end of the base; the base, the first side wall portion and the second side wall portion jointly forming a receiving space for at least partially receiving a mating connector; a plurality of insulating protrusions protruding into the receiving space; a plurality of terminal modules, each terminal module being assembled to a corresponding insulating protrusion; and a plurality of metal shield surrounding members, each metal shield surrounding member being sleeved on the corresponding insulating protrusion; wherein the metal shield surrounding member includes a surrounding portion and a mounting portion extending downwardly from the surrounding portion; the surrounding portion includes a first side wall, a second side wall, a third side wall and a fourth side wall; the first side wall is disposed opposite to the third side wall; the second side wall is disposed opposite to the fourth side wall; the first side wall, the second side wall, the third side wall and the fourth side wall are enclosed to form a fully-enclosed shielding cavity; the mounting portion includes a sixth side wall, a seventh side wall and an eighth side wall; the sixth side wall is connected to the second side wall and is located on a same side of the metal shield surrounding member; the seventh side wall is connected to the third side wall and is located on a same side of the metal shield surrounding member; the eighth side wall is connected to the fourth side wall and is located on a same side of the metal shield surrounding member; and the seventh side wall protrudes outwardly beyond the third side wall along a direction away from the third side wall; and the eighth side wall protrudes outwardly beyond the fourth side wall along a direction away from the fourth side wall.

In order to achieve the above object, the present disclosure adopts the following technical solution: a backplane connector, including: a housing including a base, a first side wall portion extending upwardly from one end of the base, and a second side wall portion extending upwardly from another end of the base; the base, the first side wall portion and the second side wall portion jointly forming a receiving space for at least partially receiving a mating connector; the base defining a plurality of receiving grooves extending through the base; and a plurality of mounting modules assembled to the receiving grooves; each mounting module including an insulating body, a terminal module installed in the insulating body, and a metal shield surrounding member sleeved on the insulating body; wherein the metal shield surrounding member includes a surrounding portion and a mounting portion extending downwardly from the surrounding portion; the surrounding portion includes a first side wall, a second side wall, a third side wall and a fourth side wall; the first side wall is disposed opposite to the third side wall; the second side wall is disposed opposite to the fourth side wall; the first side wall, the second side wall, the third side wall and the fourth side wall are enclosed to form a fully-enclosed shielding cavity; the mounting portion

includes a fifth side wall, a sixth side wall, a seventh side wall and an eighth side wall; the fifth side wall is disposed opposite to the seventh side wall; the sixth side wall is disposed opposite to the eighth side wall; the fifth side wall, the sixth side wall, the seventh side wall and the eighth side wall are enclosed to form another fully-enclosed shielding cavity; the fifth side wall is connected to the first side wall and is located on a same side of the metal shield surrounding member; the sixth side wall is connected to the second side wall and is located on a same side of the metal shield surrounding member; the seventh side wall is connected to the third side wall and is located on a same side of the metal shield surrounding member; the eighth side wall is connected to the fourth side wall and is located on a same side of the metal shield surrounding member; and the mounting portion is fixed in a corresponding receiving groove.

Compared with the prior art, the metal shield surrounding member in the present disclosure includes the surrounding portion and the mounting portion extending downwardly from the surrounding portion. The surrounding portion is formed by four side walls so as to form a fully-enclosed shielding cavity, thereby improving the shielding effect. Besides, the sixth side wall is connected to the second side wall and is located on the same side of the metal shield surrounding member; the seventh side wall is connected to the third side wall and is located on the same side of the metal shield surrounding member; and the eighth side wall is connected to the fourth side wall and is located on the same side of the metal shield surrounding member. In this way, the sixth side wall and the second side wall are able to form a grounding return; the seventh side wall and the third side wall are able to form a grounding return; and the eighth side wall and the fourth side wall are able to form a grounding return; thereby improving the grounding return effect of the backplane connector.

BRIEF DESCRIPTION OF DRAWINGS

FIG. 1 is a perspective view of a backplane connector assembly in accordance with a first embodiment of the present disclosure;

FIG. 2 is a partial perspective exploded view of FIG. 1;

FIG. 3 is another view of the second backplane connector in FIG. 2 when it is mounted on a second circuit board;

FIG. 4 is a perspective view of the second backplane connector in FIG. 3;

FIG. 5 is a front view of FIG. 4;

FIG. 15 is a bottom view of the housing in FIG. 11;

FIG. 16 is a front view of a terminal module in FIG. 11;

FIG. 17 is a rear view of the terminal module in FIG. 11;

FIG. 18 is a perspective schematic view of a metal shield surrounding member;

FIG. 19 is a perspective schematic view of the metal shield surrounding member sleeved on the terminal module;

FIG. 20 is a front view of FIG. 19;

FIG. 21 is a partial perspective exploded view of the second backplane connector;

FIG. 22 is another partial perspective exploded view of the second backplane connector;

FIG. 23 is a partial enlarged view of a circled part M in FIG. 22;

FIG. 24 is a partially exploded perspective view of FIG. 22 from another angle;

FIG. 25 is a partial enlarged view of a circled part N in FIG. 24;

FIG. 26 is a schematic cross-sectional view taken along line O-O in FIG. 4;

FIG. 27 is a schematic perspective view of a second backplane connector installed on a second circuit board in accordance with a second embodiment of the present disclosure;

FIG. 28 is an exploded perspective view of the second backplane connector and the second circuit board in FIG. 27;

FIG. 29 is a front view of the second backplane connector in FIG. 27;

FIG. 30 is a rear view of FIG. 29;

FIG. 31 is a top view of FIG. 29;

FIG. 32 is a partially enlarged view of a frame part A in FIG. 31;

FIG. 33 is a bottom view of FIG. 29;

FIG. 34 is a partial perspective exploded view of the second backplane connector in FIG. 28;

FIG. 35 is a partial perspective exploded view of FIG. 34 from another angle;

FIG. 36 is a partially enlarged view of a circled part B in FIG. 34;

FIG. 37 is a partially enlarged view of a circled part C in FIG. 35;

FIG. 38 is a partial perspective exploded view of a terminal module in FIG. 34;

FIG. 39 is a partial perspective exploded view of FIG. 38 from another angle;

FIG. 40 is a perspective exploded view of an insulating body and the terminal module in FIG. 38;

FIG. 41 is a perspective exploded view of FIG. 40 from another angle;

FIG. 42 is a perspective exploded view of FIG. 40 from yet another angle;

FIG. 43 is a front view of the terminal module in FIG. 40;

FIG. 44 is a rear view of FIG. 43;

FIG. 45 is a schematic cross-sectional view taken along line D-D in FIG. 27; and

FIG. 46 is a partial enlarged view of a frame part E in FIG. 45.

DETAILED DESCRIPTION

Exemplary embodiments will be described in detail here, examples of which are shown in drawings. When referring to the drawings below, unless otherwise indicated, same numerals in different drawings represent the same or similar elements. The examples described in the following exemplary embodiments do not represent all embodiments consistent with this application. Rather, they are merely examples of devices and methods consistent with some aspects of the application as detailed in the appended claims.

The terminology used in this application is only for the purpose of describing particular embodiments, and is not intended to limit this application. The singular forms "a", "said", and "the" used in this application and the appended

claims are also intended to include plural forms unless the context clearly indicates other meanings.

It should be understood that the terms "first", "second" and similar words used in the specification and claims of this application do not represent any order, quantity or importance, but are only used to distinguish different components. Similarly, "an" or "a" and other similar words do not mean a quantity limit, but mean that there is at least one; "multiple" or "a plurality of" means two or more than two. Unless otherwise noted, "front", "rear", "lower" and/or "upper" and similar words are for ease of description only and are not limited to one location or one spatial orientation. Similar words such as "include" or "comprise" mean that elements or objects appear before "include" or "comprise" cover elements or objects listed after "include" or "comprise" and their equivalents, and do not exclude other elements or objects. The term "a plurality of" mentioned in the present disclosure includes two or more.

Hereinafter, some embodiments of the present disclosure will be described in detail with reference to the accompanying drawings. In the case of no conflict, the following embodiments and features in the embodiments can be combined with each other.

Referring to FIGS. 1 and 2, a first embodiment of the present disclosure discloses a backplane connector assembly which includes a first backplane connector 100, a second backplane connector 200' for mating with the first backplane connector 100, a first circuit board 301 mounted with the first backplane connector 100, and a second circuit board 302 mounted with the second backplane connector 200'. In the illustrated embodiment of the present disclosure, the first backplane connector 100 and the second backplane connector 200' are mated in an orthogonal manner. The first circuit board 301 is perpendicular to the second circuit board 302.

Referring to FIGS. 3 to 11, the second backplane connector 200' includes a housing 21', a plurality of terminal modules 22' assembled to the housing 21', a plurality of metal shield surrounding members 23' fixed to the second housing 21' and enclosing corresponding terminal modules 22', and a mounting block 24' mounted to the housing 21'.

Referring to FIGS. 9 and 13 to 15, the housing 21' is made of insulating material and includes a base 210', a first side wall portion 21' extending upwardly from one side of the base 210', and a second side wall portion 22' extending upwardly from the other side of the base 210'. The base 210', the first side wall portion 21' and the second side wall portion 22' jointly form a receiving space 213' for receiving a part of the first backplane connector 100. In the illustrated embodiment of the present disclosure, the first side wall portion 21' and the second side wall portion 22' are parallel to each other and both are perpendicular to the base 210'.

In the illustrated embodiment of the present disclosure, the housing 21' further includes a plurality of insulating protrusions 214' integrally extending from the base 210'. The plurality of insulating protrusions 214' are spaced apart from one another. The plurality of insulating protrusions 214' extend upwardly into the receiving space 213'. The terminal modules 22' are installed in the insulating protrusions 214'. The plurality of insulating protrusions 214' are disposed in multiple rows along a front-rear direction. The insulating protrusions 214' in two adjacent rows are disposed in a staggered manner, that is, the insulating protrusions 214' in the same position in two adjacent rows are not in alignment with each other in the front-rear direction. The base 210' includes a top surface 2101' exposed in the receiving space 213', a bottom surface 2102' opposite to the top surface 2101', two mounting protrusions 2103' respectively protrud-

ing downwardly from opposite sides of the bottom surface 2102', and a receiving groove 2100' located between the two mounting protrusions 2103'. The receiving groove 2100' is adapted for receiving the mounting block 24'.

Referring to FIG. 14, the base 210' includes a plurality of positioning grooves 2104' extending through the top surface 2101'. In the illustrated embodiment of the present disclosure, each positioning groove 2104' is substantially U-shaped. The positioning groove 2104' is arranged around the corresponding insulating protrusion 214' and is used to install the corresponding metal shield surrounding member 23'. Specifically, each positioning groove 2104' includes a first positioning groove 2104a' extending along the front-rear direction, a second positioning groove 2104b' parallel to the first positioning groove 2104a', and a third positioning groove 2104c' communicating the first positioning groove 2104a' and the second positioning groove 2104b'. The third positioning groove 2104c' is perpendicular to the first positioning groove 2104a' and the second positioning groove 2104b'. In the illustrated embodiment of the present disclosure, each positioning groove 2104' also extends through the bottom surface 2102' so as to communicate with the receiving groove 2100'.

Referring to FIGS. 12 and 13, the bottom surface 2102' of the base 210' is also provided with a plurality of terminal receiving grooves 2105', a plurality of positioning protrusions 2106' located on both sides of each terminal receiving groove 2105, and a positioning hole 2107' for mating with the mounting block 24'. The terminal receiving groove 2105' extends through the bottom surface 2102' and is recessed into the insulating protrusion 214. Referring to FIG. 12, each insulating protrusion 214' is roughly cuboid shaped and includes an upper end surface 2141', a communicating groove 2142' extending through the upper end surface 2141', and a terminal receiving hole located at the bottom of the communicating groove 2142'. The terminal receiving hole communicates with the terminal receiving groove 2105'. In the illustrated embodiment of the present disclosure, the terminal receiving hole includes a first terminal receiving hole 2143' and a second terminal receiving hole 2144' arranged in parallel. Both the first terminal receiving hole 2143' and the second terminal receiving hole 2144' are round holes. The housing 21' is further provided with a partition 2145' for separating the first terminal receiving hole 2143' and the second terminal receiving hole 2144'. The partition 2145' has a bottom surface 2145a'. Four corners of the upper end surface 2141' include guiding inclined surfaces 2141a' for guiding installation of the metal shield surrounding member 23'. Referring to FIG. 14, the communicating groove 2142' includes a first arc-shaped groove 2142a' corresponding to the first terminal receiving hole 2143', a second arc-shaped groove 2142b' corresponding to the second terminal receiving hole 2144', and a straight slot 2142c' communicating the first arc-shaped groove 2142a' and the second arc-shaped groove 2142b'. The arc of the first arc-shaped groove 2142a' is a major arc, and the center of the major arc overlaps with the center of the first terminal receiving hole 2143'. Similarly, the arc of the second arc-shaped groove 2142b' is a major arc and the center of the major arc overlaps with the center of the second terminal receiving hole 2144'.

Referring to FIG. 9, the first side wall portion 21' includes a first top surface 2111', a first inner side surface 2112', a plurality of first protrusions 2113' protruding inwardly from the first inner side surface 2112' into the receiving space 213', and a plurality of first positioning groove 2114' each of which is located between two adjacent first protrusions

2113'. In the illustrated embodiment of the present disclosure, the first positioning groove **2114'** is a dovetail groove. The first positioning groove **2114'** has two oppositely arranged inclined surfaces, thereby making the width of the first positioning groove **2114'** close to the first inner side surface **2112'** be larger than the width of the first positioning groove **2114'** away from the first inner side surface **2112'**. In addition, the first top surface **2111'** has a first guiding inclined surface **2111a'** inclined toward the receiving space **213'** and a notch **2111b'** extending upwardly through the first top surface **2111'**. The notch **2111b'** can serve an identification function to prevent the first backplane connector **100** from being inserted at a wrong angle. The first guiding inclined surface **2111a'** further extends to the top of the plurality of first protrusions **2113'**.

Referring to FIG. 10, the second side wall portion **22'** includes a second top surface **2121'**, a second inner side surface **2122'**, a plurality of second protrusions **2123'** protruding inwardly from the second inner side surface **2122'** into the receiving space **213'**, and a plurality of second positioning grooves **2124'** each of which is located between two adjacent second protrusions **2123'**. In the illustrated embodiment of the present disclosure, the second positioning groove **2124'** is a dovetail groove. The second positioning groove **2124'** has two opposite inclined surfaces, thereby making the width of the second positioning groove **2124'** close to the second inner side surface **2122'** be larger than the width of the second positioning groove **2124'** away from the second inner side surface **2122'**. In addition, the second top surface **2121'** has a second guiding inclined surface **2121a'** which is inclined toward the receiving space **213'**. The second guiding inclined surface **2121a'** further extends to the top of the plurality of second protrusions **2123'**. The first guiding inclined surface **2111a'** and the second guiding inclined surface **2121a'** are used to guide the first backplane connector **100** to be inserted into the receiving space **213'**. In the illustrated embodiment of the present disclosure, the first protrusions **2113'** and the second protrusions **2123'** are symmetrically disposed on opposite sides of the housing **21'**. The first positioning grooves **2114'** and the second positioning grooves **2124'** are also symmetrically disposed on opposite sides of the housing **21'**.

Referring to FIGS. 16 and 17, each terminal nodule **22'** includes a first signal terminal **221'**, a second signal terminal **222'**, and an insulating block **223'** fixed to the first signal terminal **221'** and the second signal terminal **222'**. In an embodiment of the present disclosure, the first signal terminal **221'** and the second signal terminal **222'** are insert-molded with the insulating block **223'**. In an embodiment of the present disclosure, the first signal terminal **221'** and the second signal terminal **222'** form a pair of differential signal terminals. In the illustrated embodiment of the present disclosure, the first signal terminal **221'** and the second signal terminal **222'** are symmetrically arranged along a central axis of the insulating block **223'**.

The first signal terminal **221'** includes a first fixing portion **221a'** fixed to the insulating block **223'**, a first contact portion **221b'** extending upwardly from the first fixing portion **221a'**, and a first mounting foot **221c'** extending downwardly from the first fixing portion **221a'**. The first mounting foot **221c'** has a first fisheye hole **221c1'** so that the first mounting foot **221c'** has a certain elasticity. As a result, it facilitates pressing the first mounting foot **221c'** into the conductive hole of the second circuit board **302** so as to achieve electrical conduction. The first contact portion **221b'** has a two-half structure and includes a first contact piece **221b1'**, a second contact piece **221b2'**, and a first insertion

hole **2210'** located between the first contact piece **221b1'** and the second contact piece **221b2'**. The first contact piece **221b1'** and the second contact piece **221b2'** are separated by two first slots **221b3'**, so that the first contact portion **221b'** has better elasticity, thereby improving the reliability of mating with the conductive terminals of a mating connector. In addition, the first contact piece **221b1'** also includes a first flared portion **221b4'** at its end. The second contact piece **221b2'** also includes a second flared portion **221b5'** at its end. The first flared portion **221b4'** and the second flared portion **221b5'** form a first bell mouth **221b6'** communicating with the first insertion hole **2210'** in order to guide the insertion of the conductive terminal of the mating connector.

The second signal terminal **222'** includes a second fixing portion **222a'** fixed to the insulating block **223'**, a second contact portion **222b'** extending upwardly from the second fixing portion **222a'**, and a second mounting foot **222c'** extending downwardly from the second fixing portion **222a'**. The second mounting foot **222c'** has a second fisheye hole **222c1'** so that the second mounting foot **222c'** has a certain elasticity. As a result, it facilitates pressing the second mounting foot **222c'** into the conductive hole of the second circuit board **302** so as to achieve electrical conduction. The second contact portion **222b'** has a two-half structure and includes a third contact piece **222b1'**, a fourth contact piece **222b2'**, and a second insertion hole **2220'** located between the third contact piece **222b1'** and the fourth contact piece **222b2'**. The third contact piece **222b1'** and the fourth contact piece **222b2'** are separated by two second slots **222b3'**, so that the second contact portion **222b'** has better elasticity, thereby improving the reliability of mating with the conductive terminals of a mating connector. In addition, the third contact piece **222b1'** also includes a third flared portion **222b4'** at its end. The fourth contact piece **222b2'** also includes a fourth flared portion **222b5'** at its end. The third flared portion **222b4'** and the fourth flared portion **222b5'** form a second bell mouth **222b6'** communicating with the second insertion hole **2220'** in order to guide the insertion of the conductive terminal of the mating connector.

In the illustrated embodiment of the present disclosure, the insulating block **223'** includes a top portion **2231'**, a bottom portion **2232'**, and a connection portion **2233'** connecting the top portion **2231'** and the bottom portion **2232'**. The top portion **2231'** is parallel to the bottom portion **2232'**. The connection portion **2233'** is perpendicular to the top portion **2231'** and the bottom portion **2232'**. An upper end and a lower end of the connection portion **2233'** is connected to a middle of the top portion **2231'** and a middle of the bottom portion **2232'**, respectively. The top portion **2231'** has a top surface **2231a'**. The length of the top portion **2231'** is shorter than the length of the bottom portion **2232'**. The insulating block **223'** also includes a first opening **2234'** and a second opening **2235'** located between the top portion **2231'** and the bottom portion **2232'**. The first opening **2234'** and the second opening **2235'** are respectively located on both sides of the connection portion **2233'**. The first fixing portion **221a'** of the first signal terminal **221'** is partially exposed in the first opening **2234'**, and the second fixing portion **222a'** of the second signal terminal **222'** is partially exposed in the second opening **2235'** for adjusting impedance. The bottom portion **2232'** includes a bottom surface **2232a'**, two protrusions **2232b'** protruding downwardly from the bottom surface **2232a'**, and a positioning groove **2232c'** located between the two protrusions **2232b'**. The two protrusions **2232b'** respectively abut against the bottom end of the first fixing portion **221a'** and the bottom end of the second fixing portion **222a'**. The outer peripheral surface of

the insulating block 223' also includes a plurality of ribs 2236'. The outer surface of the rib 2236' is in the shape of a semicircular arc. In the illustrated embodiment of the present disclosure, the rib 2236' is located in the middle position of the two sides of the top portion 2231' and in the middle position of the front end surface of the connection portion 2233'. Of course, in other embodiments, the ribs 2236' can also be arranged on both sides of the bottom portion 2232' and/or the front end surface of the bottom portion 2232'. The rib 2236' is used to abut against the housing 21' in order to improve the reliability of installation.

Referring to FIGS. 18 to 20. In the illustrated embodiment of the present disclosure, the metal shield surrounding member 23' is formed by stamping, bending and riveting a metal plate. The metal shield surrounding member 23' includes a surrounding portion 231', a mounting portion 232' extending downwardly from the surrounding portion 231', and a plurality of mounting feet 233' extending downwardly from the mounting portion 232'. The surrounding portion 231' includes a first side wall 2311', a second side wall 2312', a third side wall 2313' and a fourth side wall 2314' which are connected in sequence. The first side wall 2311' is opposite to the third side wall 2313', and the second side wall 2312' is opposite to the fourth side wall 2314', thereby forming an enclosed shielding cavity. Of course, in other embodiments, the shielding cavity may also be of a non-enclosed type. For example, the surrounding portion 231' includes a first side wall 2311', a second side wall 2312', and a third side wall 2313' which are connected in sequence, so that the surrounding portion 231' is substantially U-shaped. In the illustrated embodiment of the present disclosure, areas of the first side wall 2311' and the third side wall 2313' are larger than areas of the second side wall 2312' and the fourth side wall 2314'. Each end of the first side wall 2311', the second side wall 2312', the third side wall 2313' and the fourth side wall 2314' includes a deflection portion 2315' which is bent inwardly. The deflection portions 2315' are independent from one another so that they can be bent independently in order to avoid mutual interference. Each deflection portion 2315' has a guiding portion 2315a' on its outer surface. By providing the deflection portions 2315', a constricted opening can be formed at the end of the metal shield surrounding member 23'. The guiding portion 2315a' can guide the deflection portions 2315' from being easily inserted into the first backplane connector 100. In the illustrated embodiment of the present disclosure, the first side wall 2311' includes a first wall portion 2311a' and a second wall portion 2311b'. The first wall portion 2311a' and the second wall portion 2311b' are fixed together by riveting. A riveting line 2311c' is formed at a junction of the first wall portion 2311a' and the second wall portion 2311b'. In other embodiments of the present disclosure, it is also possible that only the ends of at least three of the first side wall 2311', the second side wall 2312', the third side wall 2313' and the fourth side wall 2314' which are connected to each other, are provided with the deflection portions 2315' bent inwardly. For example, the deflection portions 2315' bent inwardly are provided at the ends of the second side wall 2312', the third side wall 2313' and the fourth side wall 2314' which are sequentially connected.

In the illustrated embodiment of the present disclosure, the mounting portion 232' is substantially U-shaped, and includes a connecting portion 2320', a first bending portion 2321' bent from one side of the connecting portion 2320', a second bending portion 2322' bent from the other side of the connecting portion 2320', a first tail portion 2324' extending downwardly from the first bending portion 2321', and a

second tail portion 2325' extending downwardly from the second bending portion 2322'. The first bending portion 2321' is fixed in the first positioning groove 2104a'. The second bending portion 2322' is fixed in the second positioning groove 2104b'. The connecting portion 2320' is fixed in the third positioning groove 2104c'. The connecting portion 2320' is coplanar with the third side wall 2313'. The first bending portion 2321' and the second side wall 2312' are located on the same side. The first bending portion 2321' protrudes outwardly beyond the second side wall 2312'. The second bending portion 2322' and the fourth side wall 2314' are located on the same side. The second bending portion 2322' protrudes outwardly beyond the fourth side wall 2314'. The mounting portion 232' also includes a bottom retaining portion 2326' located at the connecting portion 2320'. In the illustrated embodiment of the present disclosure, when the metal shield surrounding member 23' is not mounted to the insulating protrusion 214', the retaining portion 2326' and the connecting portion 2320' are located in the same plane. After the metal shield surrounding member 23' is installed to the insulating protrusion 214', the retaining portion 2326' is bent inwardly (that is, in a direction toward the first side wall 2311') so that the retaining portion 2326' is perpendicular to the connecting portion 2320'. The retaining portion 2326' is located in the middle of the bottom edge of the connecting portion 2320'. A plurality of first bars 2321a' are further provided on the side of the first bending portion 2321' away from the third side wall 2313'. A plurality of second bars 2322a' are further provided on the side of the second bending portion 2322' away from the third side wall 2313'. The first bars 2321a' and the second bars 2322a' both extend beyond the first side wall 2311' to be fixed the housing 21'. The first tail portion 2324' is provided with a first fisheye hole 2324a', so that the first tail portion 2324' has a certain degree of elasticity. Therefore, the first tail portion 2324' can be easily pressed into the conductive hole of the second circuit board 302 for achieving electrical conduction. The second tail portion 2325' is provided with a second fisheye hole 2325a', so that the second tail portion 2325' has a certain elasticity. Therefore, the second tail portion 2325' can be easily pressed into the conductive hole of the second circuit board 302 for achieving electrical conduction. In the illustrated embodiment of the present disclosure, the first tail portion 2324' and the second tail portion 2325' are arranged parallel to each other and are in alignment with each other along a left-right direction. The first tail portion 2324' and the second tail portion 2325' are perpendicular to the first mounting foot 221c' and the second mounting foot 222c'.

Referring to FIGS. 22 to 26, the mounting block 24' includes a plurality of mounting bars 241' arranged in a staggered manner and connected as a whole. Each mounting bar 241' includes a positioning groove 242' for positioning the mounting portion 232'. Specifically, each mounting bar 241' includes a plurality of openings 243' in a substantially rectangular shape, and the openings 243' of two adjacent rows of the mounting bars 241' are arranged in a staggered manner. Two adjacent openings 243' on the same mounting bar 241' are separated by a partition wall 244' located between the two adjacent openings 243'. The mounting block 24' includes a first inner side surface 2411', a second inner side surface 2412' opposite to the first inner side surface 2411', a third inner side surface 2413' connecting the first inner side surface 2411' and the second inner side surface 2412', and a fourth inner side surface 2414' connecting the first inner side surface 2411' and the second inner side surface 2412'. The fourth inner side surface 2414' is

opposite to the third inner side surface 2413'. Opposite ends of the fourth inner side surface 2414' include a first opening 2414a' and a second opening 2414b', respectively. In addition, opposite ends of the fourth inner side surface 2414' include a first bell mouth 2414c' located above a first opening 2414a' and a second bell mouth 2414d' located above a second opening 2414b'. The first inner side surface 2411', the second inner side surface 2412' and the third inner side surface 2413' are connected to form a U-shape configuration for receiving the mounting portion 232'. The first bell mouth 2414c' and the first opening 2414a' are used to allow the first tail portions 2324' to pass through and achieve positioning. The second bell mouth 2414d' and the second opening 2414b' are used to allow the second tail portions 2325' to pass through and achieve positioning. In an embodiment of the present disclosure, the mounting block 24' is made of electroplated plastic so as to achieve a better shielding effect. The mounting block 24' includes a positioning post 245' for mating with the positioning hole 2107'.

When assembling, firstly, the plurality of metal shield surrounding members 23' are sleeved on the insulating protrusions 214' along a top-to-bottom direction, so that the surrounding portions 231' enclose the insulating protrusions 214'. The U-shaped mounting portions 232' are inserted into the U-shaped positioning grooves 2104'. The first tail portions 2324' and the second tail portions 2325' respectively extend through the first positioning grooves 2104a' and the second positioning grooves 2104b'. The first tail portions 2324' and the second tail portions 2325' extend beyond the bottom surface 2102' and are exposed in the receiving groove 2100'. The mounting portions 232' are partially exposed in the receiving groove 2100' to increase the shielding length of the first signal terminal 221' and the second signal terminal 222'. When the metal shield surrounding members 23' are installed in place, the first bars 2321a' and the second bars 2322a' will pierce the inner wall of the terminal receiving grooves 2105' so as to improve the fixing force.

Secondly, the terminal modules 22' are inserted into the corresponding positioning grooves 2104' along a bottom-to-top direction. At this time, the ribs 2236' of the insulating blocks 223' press against the inner walls of the terminal receiving grooves 2105' so as to improve the installation reliability. When the terminal modules 22' are installed in place, top surfaces 2231a' of the insulating blocks 223' abut against bottom surfaces 2145a' of the partition 2145' in order to achieve position restriction. The first contact portions 221b' of the first signal terminals 221' and the second contact portions 222b' of the second signal terminals 222' respectively extend into the first terminal receiving holes 2143' and the second terminal receiving holes 2144'. The first mounting feet 221c' of the first signal terminals 221' and the second mounting feet 222c' of the second signal terminals 222' extend beyond the bottom surface 2102' and are exposed in the receiving groove 2100'.

Thirdly, the retaining portions 2326' are bent inwardly so that the retaining portions 2326' is located in the positioning grooves 2232c' and abut against the corresponding insulating blocks 223'. With this arrangement, on the one hand, the metal shield surrounding members 23' can be prevented from escaping upwardly from the insulating protrusions 214', and on the other hand, the terminal modules 22' can be prevented from being separated from the housing 21'.

Finally, the mounting block 24' is installed in the receiving groove 2100' along the bottom-to-top direction. At this time, the U-shaped mounting portions 232' are inserted into the openings 243' of the mounting block 24' under the

guidance of the first bell mouth 2414c' and the second bell mouth 2414d'. At this time, the first bending portions 2321' abut against the first inner side surfaces 2411'. The second bending portions 2322' abut against the second inner side surfaces 2412'. The connecting portions 2320' abut against the fourth inner side surfaces 2414'. The first tail portions 2324' and the second tail portions 2325' of the metal shield surrounding members 23', the first mounting feet 221c' of the first signal terminals 221', and the second mounting feet 222c' of the second signal terminals 222' extend through the openings 243' of the mounting block 24' to be electrically connected to the second circuit board 302.

When the first backplane connector 100 is mated with the second backplane connector 200', the first housing 1 of the first backplane connector 100 is inserted into the receiving space 213' of the housing 21' of the second backplane connector 200'. The surrounding portions 231' of the terminal modules 22' of the second backplane connector 200' are inserted into the first terminal modules 2 of the first backplane connector 100 under the guidance of the deflection portions 2315'.

Referring to FIG. 27 to FIG. 46, the second backplane connector 200' in a second embodiment of the present disclosure includes a housing 21', a plurality of mounting modules 25' mounted to the housing 21', and a mounting block 24' mounted to the housing 21'. Each mounting module 25' includes an insulating body 26', a terminal module 22' installed in the insulating body 26', and a metal shield surrounding member 23' sleeved on the insulating body 26'.

Referring to FIG. 34 and FIG. 35, the housing 21' is made of insulating material and includes a base 210', a first side wall portion 211' extending upwardly from one side of the base 210', and a second side wall portion 212' extending upwardly from the other side of the base 210'. The base 210', the first side wall portion 211' and the second side wall portion 212' jointly form a receiving space 213' for receiving a part of the first backplane connector 100. In the illustrated embodiment of the present disclosure, the first side wall portion 211' and the second side wall portion 212' are parallel to each other and both are perpendicular to the base 210'.

In the illustrated embodiment of the present disclosure, the base 210' includes a top surface 2101' exposed in the receiving space 213', a bottom surface 2102' opposite to the top surface 2101', two mounting protrusions 2103' respectively protruding downwardly from opposite sides of the bottom surface 2102', and a receiving groove 2100' located between the two mounting protrusions 2103'. The receiving groove 2100' is adapted for receiving the mounting block 24'.

As shown in FIG. 34 to FIG. 37, the base 210' further includes a plurality of receiving grooves 2108' extending through the top surface 2101' and the bottom surface 2102'. The plurality of receiving grooves 2108' are arranged in multiple rows along a front-rear direction. The receiving grooves 2108' in two adjacent rows are staggered. That is, the receiving grooves 2108' at a corresponding position in two adjacent rows are not aligned along the front-rear direction. In the illustrated embodiment of the present disclosure, each receiving groove 2108' includes a main groove 2108a' in the middle, a first groove 2108b' located on one side of the main groove 2108a', and a second groove 2108c' located on the other side of the main groove 2108a'. In the illustrated embodiment of the present disclosure, the first groove 2108b' is an arc-shaped groove which is recessed in a direction away from the second groove 2108c'. The second

groove 2108c' is an arc groove which is recessed in a direction away from the first groove 2108b'. The main groove 2108a' includes a first arc-shaped surface 2108a1', a second arc-shaped surface 2108a2', a third arc-shaped surface 2108a3' and a fourth arc-shaped surface 2108a4' which are located at four corners thereof. The first groove 2108b' is located in the middle of the first arc-shaped surface 2108a1' and the third arc-shaped surface 2108a3'; and the second groove 2108c' is located in the middle of the second arc-shaped surface 2108a2' and the fourth arc-shaped surface 2108a4', so as to maintain the symmetry of the receiving groove 2108'. In the illustrated embodiment of the present disclosure, both the first groove 2108b' and the second groove 2108c' extend upwardly through the top surface 2101'. However, neither the first groove 2108b' nor the second groove 2108c' extends downwardly through the bottom surface 2102'. The base 210' includes a first support surface 2108b1' at a bottom of the first groove 2108b' and a second support surface 2108c1' located at a bottom of the second groove 2108c'.

Referring to FIG. 34, the first side wall portion 211' includes a first top surface 2111', a first inner side surface 2112', a plurality of first protrusions 2113' protruding inwardly from the first inner side surface 2112' into the receiving space 213', and a plurality of first positioning groove 2114' each of which is located between two adjacent first protrusions 2113'. In the illustrated embodiment of the present disclosure, the first positioning groove 2114' is a dovetail groove. The first positioning groove 2114' has two oppositely arranged inclined surfaces, thereby making the width of the first positioning groove 2114' close to the first inner side surface 2112' be larger than the width of the first positioning groove 2114' away from the first inner side surface 2112'. In addition, the first top surface 2111' has a first guiding inclined surface 2111a' inclined toward the receiving space 213' and a notch 2111b' extending upwardly through the first top surface 2111'. The notch 2111b' can serve an identification function to prevent the first backplane connector 100 from being inserted at a wrong angle. The first guiding inclined surface 2111a' further extends to the top of the plurality of first protrusions 2113'.

Referring to FIG. 35, the second side wall portion 212' includes a second top surface 2121', a second inner side surface 2122', a plurality of second protrusions 2123' protruding inwardly from the second inner side surface 2122' into the receiving space 213', and a plurality of second positioning groove 2124' each of which is located between two adjacent second protrusions 2123'. In the illustrated embodiment of the present disclosure, the second positioning groove 2124' is a dovetail groove. The second positioning groove 2124' has two opposite inclined surfaces, thereby making the width of the second positioning groove 2124' close to the second inner side surface 2122' be larger than the width of the second positioning groove 2124' away from the second inner side surface 2122'. In addition, the second top surface 2121' has a second guiding inclined surface 2121a' which is inclined toward the receiving space 213'. The second guiding inclined surface 2121a' further extends to the top of the plurality of second protrusions 2123'. The first guiding inclined surface 2111a' and the second guiding inclined surface 2121a' are used to guide the first backplane connector 100 to be inserted into the receiving space 213'. In the illustrated embodiment of the present disclosure, the first protrusions 2113' and the second protrusions 2123' are symmetrically disposed on opposite sides of the housing 21'.

The first positioning grooves 2114' and the second positioning grooves 2124' are also symmetrically disposed on opposite sides of the housing 21'.

Referring to FIG. 40 to FIG. 42, the insulating body 26' includes a base portion 260', a first extension block 261' extending upwardly from one side of the base portion 260', and a second extension block 262' extending upwardly from the other side of the base portion 260'. The base portion 260' includes an upper surface 2601', a lower surface 2602', at least one terminal receiving hole extending upwardly through the upper surface 2601', and an accommodating space 2603' extending downwardly through the lower surface 2602'. In the illustrated embodiment of the present disclosure, the at least one terminal receiving hole includes a first terminal receiving hole 2143' and a second terminal receiving hole 2144' arranged in parallel. Both the first terminal receiving hole 2143' and the second terminal receiving hole 2144' are square holes. The base portion 260' is further provided with a partition portion 2145' for separating the first terminal receiving hole 2143' from the second terminal receiving hole 2144'.

In the illustrated embodiment of the present disclosure, both the first extension block 261' and the second extension block 262' are integrally formed with the base portion 260'. The first extension block 261' includes an outer first side surface 2611' and a first positioning groove 2612' recessed inwardly from the first side surface 2611'. The second extension block 262' includes an outer second side surface 2621' and a second positioning groove 2622' recessed inwardly from the second side surface 2621'. In the illustrated embodiment of the present disclosure, the first positioning groove 2612' extends upwardly through the top surface of the first extension block 261'. The second positioning groove 2622' extends upwardly through the top surface of the second extension block 262'. In the illustrated embodiment of the present disclosure, the first positioning groove 2612' does not extend inwardly through the first extension block 261'. The second positioning groove 2622' does not extend inwardly through the second extension block 262'. As a result, on the one hand, such design helps to improve the structural strength of the insulating body 26'; on the other hand, it prevents the metal shield surrounding member 23' from extending from the first positioning groove 2612' and the second positioning groove 2622' into a space between the first extension block 261' and the second extension block 262', thereby reducing the risk of short circuit caused by the metal shield surrounding member 23' being in contact with the signal terminals.

Referring to FIG. 43 and FIG. 44, each terminal module 22' includes a first signal terminal 221', a second signal terminal 222', and an insulating block 223' fixed to the first signal terminal 221' and the second signal terminal 222'. In an embodiment of the present disclosure, the first signal terminal 221' and the second signal terminal 222' are insert-molded with the insulating block 223'. In an embodiment of the present disclosure, the first signal terminal 221' and the second signal terminal 222' form a pair of differential signal terminals. In the illustrated embodiment of the present disclosure, the first signal terminal 221' and the second signal terminal 222' are symmetrically arranged along a central axis of the insulating block 223'.

The first signal terminal 221' includes a first fixing portion 221a' fixed to the insulating block 223', a first contact portion 221b' extending upwardly from the first fixing portion 221a', and a first mounting foot 221c' extending downwardly from the first fixing portion 221a'. The first mounting foot 221c' has a first fisheye hole 221c1' so that the

first mounting foot 221c' has a certain elasticity. As a result, it facilitates pressing the first mounting tool 221c' into the conductive hole of the second circuit board 302 so as to achieve electrical conduction. The first contact portion 221b' has a two-half structure and includes a first contact piece 221b1', a second contact piece 221b2', and a first insertion hole 2210' located between the first contact piece 221b1' and the second contact piece 221b2'. The first contact piece 221b1' and the second contact piece 2202' are separated by two first slots 2211b', so that the first contact portion 221b' has better elasticity, thereby improving the reliability of mating with the conductive terminals of a mating connector. In addition, the first contact piece 221b1' also includes a first flared portion 221b4' at its end. The second contact piece 221b2' also includes a second flared portion 221b5' at its end. The first flared portion 221b4' and the second flared portion 221b5' form a first bell mouth 221b6' communicating with the first insertion hole 2210' in order to guide the insertion of the conductive terminal of the mating connector.

The second signal terminal 222' includes a second fixing portion 222a' fixed to the insulating block 223', a second contact portion 222b' extending upwardly from the second fixing portion 222a', and a second mounting foot 222c' extending downwardly from the second fixing portion 222a'. The second mounting foot 222c' has a second fisheye hole 222c1' so that the second mounting foot 222c' has a certain elasticity. As a result, it facilitates pressing the second mounting foot 222c' into the conductive hole of the second circuit board 302 so as to achieve electrical conduction. The second contact portion 222b' has a two-half structure and includes a third contact piece 222b1', a fourth contact piece 222b2', and a second insertion hole 2220' located between the third contact piece 222b1' and the fourth contact piece 222b2'. The third contact piece 222b1' and the fourth contact piece 222b2' are separated by two second slots 222b3', so that the second contact portion 222b' has better elasticity, thereby improving the reliability of mating with the conductive terminals of a mating connector. In addition, the third contact piece 222b1' also includes a third flared portion 222b4' at its end. The fourth contact piece 222b2' also includes a fourth flared portion 222b5' at its end. The third flared portion 222b4' and the fourth flared portion 222b5' form a second bell mouth 222b6' communicating with the second insertion hole 2220' in order to guide the insertion of the conductive terminal of the mating connector.

In the illustrated embodiment of the present disclosure, the insulating block 223' includes a top portion 2231', a bottom portion 2232', and a connection portion 2233' connecting the top portion 2231' and the bottom portion 2232'. The top portion 2231' is parallel to the bottom portion 2232'. The connection portion 2233' is perpendicular to the top portion 2231' and the bottom portion 2232'. An upper end and a lower end of the connection portion 2233' is connected to a middle of the top portion 2231' and a middle of the bottom portion 2232', respectively. The top portion 223 has a top surface 2231a'. The length of the top portion 2231' is shorter than the length of the bottom portion 2232'. The insulating block 223' also includes a first opening 2234' and a second opening 2235' located between the top portion 2231' and the bottom portion 2232'. The first opening 2234' and the second opening 2235' are respectively located on both sides of the connection portion 2233'. The first fixing portion 221a' of the first signal terminal 221' is partially exposed in the first opening 2234', and the second fixing portion 222a' of the second signal terminal 222' is partially exposed in the second opening 2235' for adjusting impedance. The bottom portion 2232' includes a bottom surface

2232a', two protrusions 2232b' protruding downwardly from the bottom surface 2232a', and a positioning groove 2232c' located between the two protrusions 2232b'. The two protrusions 2232b' respectively abut against the bottom end of the first fixing portion 221a' and the bottom end of the second fixing portion 222a'. The outer peripheral surface of the insulating block 223' also includes a plurality of ribs 2236'. The outer surface of the rib 2236' is in the shape of a semicircular arc. In the illustrated embodiment of the present disclosure, the rib 2236' is located in the middle position of the two sides of the top portion 2231' and in the middle position of the front end surface of the connection portion 2233'. Of course, in other embodiments, the ribs 2236' can also be arranged on both sides of the bottom portion 2232' and/or the front end surface of the bottom portion 2232'. The rib 2236' is used to abut against the insulating body 26' in order to improve the reliability of installation.

Referring to FIG. 38, FIG. 39 and FIG. 46, in the illustrated embodiment of the present disclosure, the metal shield surrounding member 23' is formed by stamping, bending and riveting a metal plate. The metal shield surrounding member 23' includes a surrounding portion 231', a mounting portion 232' extending downwardly from the surrounding portion 231', a plurality of mounting feet 233' extending downwardly from the mounting portion 232', and a positioning protrusion located between the surrounding portion 231' and the mounting portion 232'. The surrounding portion 231' includes a first side wall 2311', a second side wall 2312', a third side wall 2313' and a fourth side wall 2314'. The first side wall 2311' is opposite to the third side wall 2313', and the second side wall 2312' is opposite to the fourth side wall 2314', thereby forming a fully-enclosed shielding cavity. In the illustrated embodiment of the present disclosure, areas of the first side wall 2311' and the third side wall 2313' are larger than areas of the second side wall 2312' and the fourth side wall 2314'. Each end of the first side wall 2311', the second side wall 2312', the third side wall 2313' and the burr side wall 2314' includes a deflection portion 2315' which is bent inwardly. The deflection portions 2315' are independent from one another so that they can be bent independently in order to avoid mutual interference. Each deflection portion 2315' has a guiding portion 2315a' on its outer surface. By providing the deflection portions 2315', a constricted opening can be formed at the end of the metal shield surrounding member 23'. The guiding portion 2315a' can guide the deflection portions 2315' from being easily inserted into the first backplane connector 100. In the illustrated embodiment of the present disclosure, the first side wall 2311' includes a first wall portion 2311a' and a second wall portion 2311b'. The first wall portion 2311a' and the second wall portion 2311b' are fixed together by riveting. A riveting line 2311c' is formed at a junction of the first wall portion 2311a' and the second wall portion 2311b'. In other embodiments of the present disclosure, it is also possible that only the ends of at least three of the first side wall 2311', the second side wall 2312', the third side wall 2313' and the fourth side wall 2314' which are connected to each other, are provided with the deflection portions 2315' bent inwardly. For example, the deflection portions 2315' bent inwardly are provided at the ends of the second side wall 2312', the third side wall 2313' and the fourth side wall 2314' which are sequentially connected.

In the illustrated embodiment of the present disclosure, the mounting portion 232' includes a fifth side wall 232a', a sixth side wall 232b', a seventh side wall 232c' and an eighth side wall 232d'. The fifth side wall 232a' is opposite to the

seventh side wall 232c', and the sixth side wall 232b' is opposite to the eighth side wall 232d', so as to form a fully-enclosed shielding cavity. In the illustrated embodiment of the present disclosure, an area of each of the fifth side wall 232a' and the seventh side wall 232c' is larger than an area of each of the sixth side wall 232b' and the eighth side wall 232d'.

The fifth side wall 232a' and the first side wall 2311' are located on a same side of the metal shield surrounding member 23'. The sixth side wall 232b' and the second side wall 2312' are located on a same side of the metal shield surrounding member 23'. The seventh side wall 232c' and the third side wall 2313' are located on a same side of the metal shield surrounding member 23'. The eighth side wall 232d' and the fourth side wall 2314' are located on a same side of the metal shield surrounding member 23'.

In the illustrated embodiment of the present disclosure, the fifth side wall 232a' is located in a same plane as the first side wall 2311', that is, the fifth side wall 232a' is flush with the first side wall 2311'. The sixth side wall 232b' is located in a same plane as the second side wall 2312', that is, the sixth side wall 232b' is flush with the second side wall 2312'. As shown in FIG. 46, the seventh side wall 232c' protrudes beyond the third side wall 2313'. The eighth side wall 232d' protrudes beyond the fourth side wall 2314'. The positioning protrusion includes a first positioning protrusion 2341' located between the seventh side wall 232c' and the third side wall 2313', and a second positioning protrusion 2342' located between the eighth side wall 232d' and the fourth side wall 2314'. The first positioning protrusion 2341' is arc-shaped and protrudes beyond the seventh side wall 232c' and the third side wall 2313'. The second positioning protrusion 2342' is arc-shaped and protrudes beyond the eighth side wall 232d' and the fourth side wall 2314'.

In the illustrated embodiment of the present disclosure, the third side wall 2313' further includes a first protruding tab 2313a' punched inwardly and locked in the first positioning groove 2612'. The fourth side wall 2314' further includes a second protruding tab 2314a' punched inwardly and locked in the second positioning groove 2622'.

The plurality of mounting feet 233' integrally extend downwardly from the seventh side wall 232c' and the eighth side wall 232d', respectively.

Referring to FIG. 35, the mounting block 24' includes a plurality of mounting bars 241' arranged in a staggered manner and connected as a whole. Each mounting bar 241' includes a positioning slot 242' for positioning the mounting portion 232'.

When assembling, the terminal module 22' and the insulating body 26' are assembled together firstly. The insulating block 223' is at least partially accommodated in the accommodating space 2603'. Then, the metal shield surrounding member 23' is sleeved on the insulating body 26' so as to form the mounting module 25'. Then, the mounting module 25' are assembled in a corresponding receiving groove 2108' of the housing 21' from top to bottom. The mounting portion 232' is locked in the main groove 2108a'. The four arc-shaped corners of the mounting portion 232' correspond to the first arc-shaped surface 2108a1', the second arc-shaped surface 2108a2', the third arc-shaped surface 2108a3' and the fourth arc-shaped surface 2108a4', so as to balance the force distribution and avoid installation inclination. The first positioning protrusion 2341' and the second positioning protrusion 2342' are locked in the first groove 2108b' and the second groove 2108c', respectively. The first positioning protrusion 2341' and the second positioning protrusion 2342' abut against the first support surface 2108b1' and the second

support surface 2108c1' respectively, so as to function as positioning and limiting. Finally, the mounting block 24' is installed in the receiving groove 2100' from bottom to top, so as to fix the mounting portion 232' of the metal shield surrounding member 23'. At this time, the mounting feet 233' of the metal shield surrounding member 23', the first mounting foot 221c' of the first signal terminal 221', and the second mounting foot 222c' of the second signal terminal 222' pass through the mounting block 24' to be electrically connected to the second circuit board 302.

When the first backplane connector 100 is mated with the second backplane connector 200', the first housing 1 of the first backplane connector 100 is inserted into the receiving space 213' of the housing 21' of the second backplane connector 200'. The surrounding portions 231' of the terminal modules 22' of the second backplane connector 200' are inserted into the first terminal modules 2 of the first backplane connector 100 under the guidance of the deflection portions 2315'.

Compared with the prior art, the metal shield surrounding member 23' of the present disclosure includes a surrounding portion 231' and a mounting portion 232' extending downwardly from the surrounding portion 231'. Both the surrounding portion 231' and the mounting portion 232' are formed by four side walls so as to form a fully-enclosed shielding cavity, thereby improving the shielding effect. In addition, the fifth side wall 232a' is connected to the first side wall 2311' and is located on the same side of the metal shield surrounding member 23'. The sixth side wall 232b' is connected to the second side wall 2312' and is located on the same side of the metal shield surrounding member 23'. The seventh side wall 232c' is connected to the third side wall 2313' and is located on the same side of the metal shield surrounding member 23'. The eighth side wall 232d' is connected to the fourth side wall 2314' and is located on the same side of the metal shield surrounding member 23'. In this way, the fifth side wall 232a' and the first side wall 2311' are able to form a grounding return; the sixth side wall 232b' and the second side wall 2312' are able to form a grounding return; the seventh side wall 232c' and the third side wall 2313' are able to form a grounding return; and the eighth side wall 232d' and the fourth side wall 2314' are able to form a grounding return; thereby improving the effect of the grounding return.

The above embodiments are only used to illustrate the present disclosure and not to limit the technical solutions described in the present disclosure. The understanding of this specification should be based on those skilled in the art. Descriptions of directions, such as "front", "rear", "left", "right", "top" and "bottom", although they have been described in detail in the above-mentioned embodiments of the present disclosure, those skilled in the art should understand that modifications or equivalent substitutions can still be made to the application, and all technical solutions and improvements that do not depart from the spirit and scope of the application should be covered by the claims of the application.

What is claimed is:

1. A backplane connector, comprising:
a housing comprising a base, a first side wall portion extending from one end of the base, and a second side wall portion extending from another end of the base; the base, the first side wall portion and the second side wall portion jointly forming a receiving space for at least partially receiving a mating connector; a plurality of insulating protrusions protruding into the receiving space;

19

a plurality of terminal modules, each terminal module being assembled to a corresponding insulating protrusion; and

a plurality of metal shield surrounding members, each metal shield surrounding member being sleeved on the corresponding insulating protrusion;

wherein the metal shield surrounding member comprises a surrounding portion and a mounting portion extending downwardly from the surrounding portion; the surrounding portion comprises a first side wall, a second side wall, a third side wall and a fourth side wall; the first side wall is disposed opposite to the third side wall, the second side wall is disposed opposite to the fourth side wall; the first side wall, the second side wall, the third side wall and the fourth side wall are enclosed to form a fully-enclosed shielding cavity;

the mounting portion comprises a sixth side wall, a seventh side wall and an eighth side wall; the sixth side wall is connected to the second side wall and is located on a same side of the metal shield surrounding member; the seventh side wall is connected to the third side wall and is located on a same side of the metal shield surrounding member; the eighth side wall is connected to the fourth side wall and is located on a same side of the metal shield surrounding member; and

the seventh side wall protrudes outwardly beyond the third side wall along a direction away from the third side wall; and the eighth side wall protrudes outwardly beyond the fourth side wall along a direction away from the fourth side wall.

2. The backplane connector according to claim 1, wherein the sixth side wall is flush with the second side wall.

3. The backplane connector according to claim 1, wherein each of the first side wall, the second side wall, the third side wall and the fourth side wall comprises a deflection portion which is bent inwardly to guide insertion of the mating connector.

4. The backplane connector according to claim 1, wherein the mounting portion comprises a fifth side wall, the fifth side wall, the sixth side wall, the seventh side wall and the eighth side wall are enclosed to form another fully-enclosed shielding cavity.

5. The backplane connector according to claim 4, wherein the fifth side wall is connected to the first side wall and is located on a same side of the metal shield surrounding member; and the fifth side wall is flush with the first side wall.

6. The backplane connector according to claim 4, wherein the metal shield surrounding member comprises a first positioning protrusion located between the seventh side wall and the third side wall, and a second positioning protrusion located between the eighth side wall and the fourth side wall;

the receiving groove comprises a main groove located in the middle, a first groove located on one side of the main groove, and a second groove located on another side of the main groove; the mounting portion is fixed in the main groove; the first positioning protrusion is fixed in the first groove; the second positioning protrusion is fixed in the second groove.

7. The backplane connector according to claim 6, wherein the first groove is an arc-shaped groove and is recessed in a direction away from the second groove; the second groove is an arc-shaped groove and is recessed in a direction away from the first groove; the base comprises a first support surface located at a bottom of the first groove, and a second support surface located at a bottom of the second groove;

20

the first positioning protrusion abuts against the first support surface; the second positioning protrusion abuts against the second support surface.

8. The backplane connector according to claim 6, wherein the main groove comprises a first arc-shaped surface, a second arc-shaped surface, a third arc-shaped surface and a fourth arc-shaped surface which are located at four corners of the main groove; the first groove is located in a middle of the first arc-shaped surface and the third arc-shaped surface; and the second groove is located in a middle of the second arc-shaped surface and the fourth arc-shaped surface.

9. The backplane connector according to claim 1, wherein each terminal module comprises a first signal terminal, a second signal terminal, and an insulating block to which the first signal terminal and the second signal terminal are fixed; the insulating protrusion comprises a base portion, a first extension block extending upwardly from one side of the base portion, and a second extension block extending upwardly from another side of the base portion; the base portion defines a first terminal receiving hole and a second terminal receiving hole; the first signal terminal and the second signal terminal are accommodated in the first terminal receiving hole and the second terminal receiving hole, respectively;

the first extension block comprises a first side surface and a first positioning groove recessed inwardly from the first side surface; the second extension block comprises a second side surface and a second positioning groove recessed inwardly from the second side surface; the third side wall comprises a first protruding tab protruding inwardly to be locked in the first positioning groove; the fourth side wall comprises a second protruding tab protruding inward to be locked in the second positioning groove.

10. The backplane connector according to claim 9, wherein the first positioning groove does not extend inwardly through the first extension block; and the second positioning groove does not extend inwardly through the second extension block.

11. A backplane connector, comprising:

a housing comprising a base, a first side wall portion extending upwardly from one end of the base, and a second side wall portion extending upwardly from another end of the base; the base, the first side wall portion and the second side wall portion jointly forming a receiving space for at least partially receiving a mating connector; the base defining a plurality of receiving grooves extending through the base; and

a plurality of mounting modules assembled to the receiving grooves; each mounting module comprising an insulating body, a terminal module installed in the insulating body, and a metal shield surrounding member sleeved on the insulating body;

wherein the metal shield surrounding member comprises a surrounding portion and a mounting portion extending downwardly from the surrounding portion; the surrounding portion comprises a first side wall, a second side wall, a third side wall and a fourth side wall; the first side wall is disposed opposite to the third side wall; the second side wall is disposed opposite to the fourth side wall; the first side wall, the second side wall, the third side wall and the fourth side wall are enclosed to form a fully-enclosed shielding cavity;

the mounting portion comprises a fifth side wall, a sixth side wall, a seventh side wall and an eighth side wall; the fifth side wall is disposed opposite to the seventh side wall; the sixth side wall is disposed opposite to the

21

eighth side wall; the fifth side wall, the sixth side wall, the seventh side wall and the eighth side wall are enclosed to form another fully-enclosed shielding cavity;

the fifth side wall is connected to the first side wall and is located on a same side of the metal shield surrounding member; the sixth side wall is connected to the second side wall and is located on a same side of the metal shield surrounding member; the seventh side wall is connected to the third side wall and is located on a same side of the metal shield surrounding member; the eighth side wall is connected to the fourth side wall and is located on a same side of the metal shield surrounding member; and

the mounting portion is fixed in a corresponding receiving groove.

12. The backplane connector according to claim 11, wherein the seventh side wall protrudes outwardly beyond the third side wall; and the eighth side wall protrudes outwardly beyond the fourth side wall.

13. The backplane connector according to claim 12, wherein the fifth side wall is flush with the first side wall; and the sixth side wall is flush with the second side wall.

14. The backplane connector according to claim 12, wherein the metal shield surrounding member comprises a first positioning protrusion located between the seventh side wall and the third side wall, and a second positioning protrusion located between the eighth side wall and the fourth side wall;

the receiving groove comprises a main groove located in the middle, a first groove located on one side of the main groove, and a second groove located on another side of the main groove; the mounting portion is fixed in the main groove; the first positioning protrusion is fixed in the first groove; the second positioning protrusion is fixed in the second groove.

15. The backplane connector according to claim 14, wherein the first groove is an arc-shaped groove and is recessed in a direction away from the second groove; the second groove is an arc-shaped groove and is recessed in a direction away from the first groove; the base comprises a first support surface located at a bottom of the first groove, and a second support surface located at a bottom of the second groove;

the first positioning protrusion abuts against the first support surface; the second positioning protrusion abuts against the second support surface.

16. The backplane connector according to claim 14, wherein the main groove comprises a first arc-shaped surface, a second arc-shaped surface, a third arc-shaped surface

22

and a fourth arc-shaped surface which are located at four corners of the main groove; the first groove is located in a middle of the first arc-shaped surface and the third arc-shaped surface; and the second groove is located in a middle of the second arc-shaped surface and the fourth arc-shaped surface.

17. The backplane connector according to claim 11, wherein the metal shield surrounding member further comprises a plurality of mounting feet extending from the mounting portion; the backplane connector further comprises a mounting block mounted to a bottom of the housing; the mounting block defines a positioning slot to position the mounting portion; the plurality of mounting feet pass through the mounting block.

18. The backplane connector according to claim 11, wherein the terminal module comprises a first signal terminal, a second signal terminal, and an insulating block to which the first signal terminal and the second signal terminal are fixed;

the insulating body comprises a base portion, a first extension block extending upwardly from one side of the base portion; and a second extension block extending upwardly from another side of the base portion; the base portion defines a first terminal receiving hole and a second terminal receiving hole; the first signal terminal and the second signal terminal are accommodated in the first terminal receiving hole and the second terminal receiving hole, respectively;

the first extension block comprises a first side surface and a first positioning groove recessed inwardly from the first side surface; the second extension block comprises a second side surface and a second positioning groove recessed inwardly from the second side surface;

the third side wall comprises a first protruding tab protruding inwardly to be locked in the first positioning groove; the fourth side wall comprises a second protruding tab protruding inward to be locked in the second positioning groove.

19. The backplane connector according to claim 18, wherein the first positioning groove does not extend inwardly through the first extension block; and the second positioning groove does not extend inwardly through the second extension block.

20. The backplane connector according to claim 18, wherein the first positioning groove extends upwardly through a top surface of the first extension block; and the second positioning groove extends upwardly through a top surface of the second extension block.
